ARRANGEMENT FOR REMOVING THE DE-
POSIT FROM THE TUBULAR SYSTEMS OF
STEAM GENERATORS WITH FORCED PAS-
SAGE OF THE OPERATING MEDIUMMartin Eule, Berlin-Spandau, Germany, assignor

8 Claims. (Cl. 122—379)

My invention relates to steam generators of the forced-flow type and it has for an object to provide apparatus of this character with means for effecting the removal of salt deposits therefrom.

5 With boilers of the drum type, salts entrained with the feed water ordinarily deposit within the drum and such deposits are ordinarily removed by "blow-down" operations. On the other hand, with a forced-flow boiler, the nature of 10 the construction does not permit of such localized salt deposition nor that method of removal, the salt being deposited along the inner walls of the tube portions over a substantial length of the latter. Hence, it is essential to provide salt 15 removal means which is essentially different in structure, relation and operation when compared to "blow-down" apparatus used with drum type boilers.

It has heretofore been proposed to provide the 20 tubular portions of the evaporation or salt deposit zone of a forced-flow boiler with outlet conduits which could be opened to effect the removal of salt deposits, together with means for increasing the operating medium pressure at the 25 point of removal when an outlet conduit is opened. The rise in pressure necessarily increases the temperature of vaporization with the result that operating medium in the liquid state 30 flows through the salt deposit zone and is discharged through an open outlet conduit, salt being dissolved and entrained by the liquid operating medium. Each of the tubular portions 35 of the salt deposit zone of a boiler may be cleaned, one by one, in this manner. This arrangement is objectionable because of the quantity of operating medium required to flow through the outlet conduit in order to effect cleaning of a tubular portion, for the quantity of water so discharged 40 may be so large as to substantially impair the operation of the generator, particularly as the storage capacity of a boiler of this type is relatively small. Also, the required operation of the feed pump to effect scavenging displaces the zone 45 of conversion of liquid to vapor in coils not being scavenged with the result that the salt deposit zone may be shifted to an undesired part of the boiler. Accordingly, this arrangement for the removal of salt deposits from forced-flow 50 boilers is objectionable, not only on account of

the heat loss, but also on account of wandering of the salt deposit zone during cleaning periods.

Therefore, it is a more specific object of my invention to provide the coils or tubular portions of the salt deposit zone of a forced-flow tubular 5 boiler with means for injecting scavenging medium into the coils so that the salt deposits therein may be dissolved, the solution being discharged through suitable outlet conduits.

These and other objects will be effected by my 10 invention as will be apparent from the following description and claims taken in connection with the accompanying drawings, forming a part of this application, in which:

Fig. 1 is a vertical sectional view showing a 15 boiler incorporating my improvement; and

Figs. 2 to 11, inclusive, are diagrammatic views showing different arrangements of the scavenging apparatus.

In Fig. 1, I show a steam generator or boiler 20 having heating spaces 5, 6 and 7 through which heated gases flow in series from combustion apparatus, at 8, to the flue 9.

Heating surface elements are arranged in the heating spaces 5, 6 and 7, for example, as follows: element 10 in the space 7; elements 11, 13 and 15 in the space 6; and elements 12 and 14 in the space 5.

Forced flow of operating medium, for example, water, is secured by means of a feed pump 30 16, the operating medium being supplied by the feed pump to the element 10 and passing from the latter in series through the elements 11, 12, 13, 14 and 15 and being discharged to the main 35 17 as superheated steam.

The elements 10, 11, 12 and 13 are so designed and so distributed in the heating spaces that at least the final portion of evaporation is effected in the element 13, that is, the arrangement and operation is such that the salt deposit 40 zone is normally confined to the element 13.

As shown, additions of heat are made to the operating medium by contact or convection in the sections 10 and 11, almost entirely radiantly in the section 12, and by contact in the element 45 13, the heat additions being such that vaporization is effected in such a manner that the salt deposit zone is included in the section 13.

Steam is normally superheated to some extent before leaving the element 13, and it is further 50

superheated in the element 14, subject mainly to radiant heat, and in the element 15, subject mainly to contact heat.

The tubular elements 10, 11, 12, 13, 14 and 15 may be arranged in any suitable manner. For example, the element 10 is shown diagrammatically as being comprised by tubular portions or coils 10a, 10b, and 10c, the tubular portions or coils being connected to the inlet header 10d and the outlet header 10e. The other elements are shown diagrammatically in a similar manner, the subscripts "a", "b", "c", "d" and "e" indicating similar parts and relations.

Scavenging medium is supplied by the conduits 21, 22 and 23 which are connected to the tubular portions or coils 13a, 13b and 13c, respectively, at the up-stream side of the salt-deposit zone, and it is discharged through outlet conduits 24, 25 and 26 connected to the coils 13a, 13b, 13c, respectively, at the down-stream side of such zone. The conduits 21, 22, 23, 24, 25 and 26 are provided with valves 21a, 22a, 23a, 24a, 25a, and 26a, respectively.

When it is desired to scavenge a tubular portion or coil, for example, the tubular portion or coil 13a, the valves 21a and 24a are opened so that scavenging medium may be supplied through the conduit 21 to dissolve deposits of salt in the tubular element or coil 13a, the solution being discharged through the conduit 24. A throttling or check valve device 17a is arranged beyond the point of connection of the discharge conduit 24 to prevent substantial back flow from the outlet manifold 13e into the coil being cleaned, whereby loss of heated operating medium is minimized. In like manner, the coils 13b and 13c are provided with back flow preventing devices 17b and 17c. As an additional medium is admitted to scavenge the tubular elements, the disadvantages of heat loss and shifting of the salt-deposit zone occasioned by the use of the operating medium for this purpose are avoided.

In Figs. 2 to 11, inclusive, there are shown diagrammatically different arrangements of tubular elements and scavenging means therefor and corresponding to the tubular elements of the section 13 of Fig. 1.

In Fig. 2, a pair of parallel-connected tubular elements 30 are included in the boiler tubular system having the feed pump 3 so that the inlet ends 31 of the tubular elements are supplied with operating medium.

Each tubular element 30 has an inlet conduit 32 for supplying scavenging medium thereto and has an outlet conduit 33 for withdrawing scavenging medium and some of the operating medium therefrom, the conduits 32 and 33 having control valves 34 and 35, respectively.

Beyond the outlet conduit 33, each tubular element 30 is provided with a device 36 for restricting backflow of operating medium into the outlet conduit 33, whereby loss of operating medium incident to scavenging is minimized. The device 36 may be of any suitable type, for example, an orifice, a valve, or a check valve.

The scavenging medium inlet and outlet conduits 32 and 33 are so related to each tubular element 30 as to include a section b of the total tubular length a of such element wherein completion of vaporization of the operating medium is effected and deposition of salts occur.

When it is desired to scavenge or remove salt deposits from a tubular element 30, the valves 34 and 35 of the associated conduits 32 and 33

are opened to permit the passage of scavenging medium through the section b. Some of the operating medium is necessarily withdrawn with the scavenging medium, however, the amount of operating medium so withdrawn is minimized due to the device 36.

In Fig. 3, instead of a pair of parallel-connected tubular elements 30, as in Fig. 2, the tubular elements are arranged in series connected groups 38, 39 and 40, the intermediate group 39 comprising parallel-connected tubular elements 41. The groups are so arranged with respect to the boiler tubular system that vaporization is completed and salts deposit in the tubular elements 41 of the intermediate group. Each of the tubular elements 41 is provided with scavenging medium supply and withdrawal conduits 32 and 33 arranged and operating similarly to those of Fig. 2.

Fig. 4 shows a further modified arrangement of tubular elements wherein, instead of the intermediate group 42 being comprised by parallel-connected tubular elements as in Fig. 3, such intermediate group is comprised by sub-groups 43 and 44, each including parallel-connected tubular elements 45. Vaporization of operating medium is completed and salt deposits occur in the tubular elements of the sub-groups.

With the arrangement of Fig. 4, it is possible to scavenge all the tubular elements of a sub-group simultaneously. Accordingly, the sub-group 43 is provided with a scavenging medium conduit 46 supplied by a pump 47, the conduit having a control valve 48 and the conduit 46 is shown as being connected to both of the tubular elements 45 of the sub-group 43. The outlet conduit 49 is also connected to both of the tubular elements 45 of the sub-group 43. With opening of the control valves 48 and 50 in the conduits 46 and 49, the pump 47 is effective to secure passage of scavenging medium in parallel through the tubular elements of the sub-group 43.

The sub-group 44 of Fig. 4 is arranged similarly to the sub-group 43 and has a similar arrangement of scavenging medium supply and discharge conduits 46 and 49 the only difference being that, instead of the supply conduit 46 being furnished with scavenging medium by a pump 47, such medium is supplied from a suitable point in the boiler system.

In Figs. 5 to 11, inclusive, there are shown scavenging arrangements including separating devices or traps 51, which serve to separate vapors and provide for continuance of flow of the latter in the boiler tubular system and minimize withdrawal thereof with the scavenging medium. The traps or separating device 51 also serve the purpose of the reverse-flow restricting device 36 already described.

Referring to Fig. 5, the tubular element 52 includes a section 53 containing the salt deposit zone, the section 53 discharging into the upper portion of the trap or separating device 51. The trap or separating device has a vapor outlet 54 communicating with the upper portion thereof and connected to the tubular portion 55 of the boiler system, and the trap is also provided with a drainage outlet or conduit 56. Scavenging medium is supplied through the conduit 57 for passage through the tubular section 53 to dissolve and entrain salt deposits. With opening of the control valves 58 and 59 in the supply and drainage conduits 57 and 56, respectively, scavenging medium passes through the tubular sec-

tion 53 along with operating medium and enters the upper portion of the trap or separating devices 51, the vapor separating from the liquid and passing through the outlet 54 for continued flow through the boiler tubular system and liquid with salts being drained from the bottom of the trap or receptacle through the conduit 56.

Fig. 6 shows an arrangement of parallel-connected tubular elements similar to Fig. 2 except that the salt deposit zones of the tubular elements have scavenging devices including traps 51.

Fig. 7 shows a pair of parallel-connected tubular elements each having salt deposit portions or zones 60 to which scavenge medium is supplied in parallel from the conduit 61 having the control valve 62. In like manner, the drainage conduit 63 is connected in parallel to the traps 51, the drainage conduit having the control valve 64. With opening of the control valves 62 and 64, it will be apparent that the salt deposit sections 60 will be scavenged in parallel.

Fig. 8 shows an arrangement of parallel-connected salt deposit zone tubular elements 66 having scavenging medium supplied thereto in parallel from the conduit 67 having a control valve 68, the element 66 discharging into a single trap or separating device 51.

Fig. 9 shows an arrangement similar in a general way to Fig. 3 except that the salt deposit tubular elements 69 of the intermediate group are, respectively, arranged to discharge into traps 51.

Fig. 10 shows an arrangement similar to Fig. 9 except that scavenging medium is supplied by the conduits 70 for flow in parallel through the salt deposit zone tubular elements and such medium is withdrawn in parallel from the traps 51 by means of a drainage conduit 71.

Fig. 11 shows a combination of the features of Figs. 8 and 10, scavenging medium being supplied by a conduit 72 for flow in parallel through the salt deposit zone tubular elements and being discharged with operating medium into a single trap 51.

From the foregoing, it will be apparent that the tubular element or section 13, arranged in a convection heating space wherein temperatures normally prevail which are low enough to prevent injury to the tubing even though salt deposits occur within the walls thereof, may have a wide variety of mechanical arrangements; however, it is a characteristic feature that scavenging medium, in addition to the operating medium, is admitted at the up-stream side of the salt deposit zone portion of each tubular element, the scavenging medium being withdrawn from the tubular element at the down-stream side of the salt deposit zone. As it is desirable to minimize the loss of operating medium incident to scavenging, devices are provided to minimize the back-flow of operating medium through the tubular element and through the scavenging outlet during scavenging periods; and any suitable device may be employed for this purpose, for example, an orifice, reverse-flow restriction, valve or trap.

I claim as my invention:

1. In a steam generator of the once-through tubular type, a section comprising tubular means wherein completion of vaporization of operating medium is effected and salts deposit, apparatus for scavenging the salt deposit zone of said section including means for introducing water to the section at the up-stream side of the salt deposit zone, said water being in addition to the operating medium supplied to the section, and means for discharging water with salts in solution

and entrained thereby from the section at the down-stream side of the salt-deposit zone.

2. In a steam generator, a tubular system including a tubular element to the inlet end of which operating medium is supplied, within which evaporation of such medium is completed, and wherein salts deposit incident to evaporation; means for introducing scavenging medium to the tubular element beyond the inlet end thereof and at the up-stream side of the salt-deposit zone; and means for withdrawing scavenging medium from the tubular element at the down-stream side of the salt-deposit zone.

3. In a steam generator, a tubular system including a tubular element to the inlet end of which operating medium is supplied, within which evaporation of operating medium is completed, and wherein salts deposit incident to evaporation; means for introducing scavenging medium to the tubular element at the up-stream side of the salt deposit zone thereof; means for withdrawing scavenging medium from the tubular element at the downstream side of the salt-deposit zone; and means for restricting reverse flow of operating medium incident to scavenging.

4. In a steam generator, a tubular system including a plurality of tubular elements within which evaporation of operating medium is completed and wherein salts deposit incident to evaporation, means for introducing scavenging medium to each tubular element at the up-stream side of the salt-deposit zone, means for withdrawing scavenging medium from each tubular element at the down-stream side of the salt-deposit zone, and means for controlling the scavenging medium admission and withdrawal means so that the tubular elements may be selectively scavenged.

5. In a steam generator, a tubular system including a plurality of parallel-connected tubular elements within which evaporation of operating medium is completed and wherein salts deposit incident to evaporation, conduit means for introducing scavenging medium to the tubular elements at the up-stream side of the salt-deposit zone thereof, conduit means for withdrawing scavenging medium from said tubular elements at the down-stream side of the salt-deposit zone, and means for controlling the conduit means so that each tubular element may be scavenged.

6. In a steam generator, a tubular system including a plurality of tubular elements within which evaporation of operating medium is completed and wherein salts deposit incident to evaporation, conduits connected to the tubular elements for introducing scavenging medium thereto at the up-stream side of the salt-deposit zone, conduits connected to the tubular elements at the down-stream side of the salt-deposit zone for withdrawing scavenging medium, and valves arranged in the respective conduits for controlling scavenging operations.

7. In a steam generator, a tubular system including a tubular element within which evaporation of operating medium is completed and wherein salts deposit incident to evaporation, a conduit connected to the tubular element at the up-stream side of the salt-deposit zone for introducing scavenging medium to the tubular element, a trap connected to the tubular element at the down-stream side of the salt-deposit zone, means providing a vapor outlet for said trap and constituting an element of said tubular system, a drainage outlet for the trap, and valves associ-

ated with said conduit and with the drainage outlet to control scavenging operations.

8. In a steam generator, a tubular system including a tubular element within which evaporation of operating medium is completed and wherein salts deposit incident to evaporation, means for introducing scavenging medium to said tubular element at the up-stream side of the salt deposit zone thereof, means providing a separation chamber into which said tubular element

discharges, the discharge end of said tubular element being arranged at the down-stream side of the salt-deposit zone, means providing a vapor outlet for said chamber and constituting an element of the tubular system, means providing a drainage outlet for the separation chamber, and valves for the scavenging medium admission means and the drainage outlet.

MARTIN EULE. 10
